CARL MILLER

INVENTOR

BY *Victor J. Evans*

ATTORNEY

WITNESS: *A. Mank*

UNITED STATES PATENT OFFICE

CARL MILLER, OF NEW YORK, N. Y.

SANITARY TELEPHONE DEVICE

Application filed August 29, 1929. Serial No. 389,257.

This invention relates to improvements in sanitary attachments for the mouthpieces of telephones, and its leading object is to provide an absorbent carrier for a vaporizing disinfectant as a resilient attaching ring, which can be snapped directly over the mouth piece of a telephone, without requiring its removal, and without influencing the action of the telephone transmitter.

10 Other objects and advantages of the invention will be hereinafter specifically pointed out, or will become apparent, as the specification proceeds.

With the above indicated objects in view, 15 the invention resides in certain novel constructions and combinations and arrangement of parts, clearly described in the following specification and fully illustrated in the accompanying drawings, which latter show 20 an embodiment of the invention as at present preferred.

In the drawings:—

Fig. 1 is a view of the attachment applied 25 to a telephone mouthpiece, shown in perspective.

Fig. 2 is a plan view of the attachment.

Fig. 3 is a detail sectional view on an enlarged scale, showing a connecting means 30 for the ends of the spring coil.

35 Referring to the drawings in detail, 5 designates an attachment consisting of a coil of spring wire forming an open tube. The spiral ends of this coil are sprung over the ends of the smaller coil 6, which is formed as

one end of the coil 5.

This smaller coil 6 is designed to provide a concealed coupling for the ends of the coil 5, and also provide means for increasing and decreasing the tensional grip of the annular 40 spring device around the mouthpiece A of the telephone transmitter B.

Within the tubular coil 5 an annular absorbent member or wick 7 is arranged. This 45 member may be formed of any absorbent woven material, or otherwise, and is charged with a disinfectant material, preferably liquid, which will emit a vapor for some time.

This attachment is forced over the mouthpiece A, so that the spring coil will grip the

base of the mouthpiece, which is in the form of a cone.

In this combination the base of the mouthpiece is formed with radially spaced openings A₂, which are approximately as deep as the width or thickness of the attachment, so that a free flow of vapor from the disinfectant into the speaking chamber of the mouthpiece will take place.

The position of the attachment on the mouthpiece is easily changed by turning the attachment about the mouthpiece. This makes it easy to adjust the attachment, to prevent the liquid disinfectant from settling in the lower part of the absorbent member or ring.

The ring of absorbent material is spaced somewhat from the outer surface of the turns of the coils, and this arrangement serves to maintain the absorbent wick material from direct contact with the hands of any person using the telephone, who might carelessly finger the device.

The whole attachment can be made to sell at an insignificant price, and can be applied without skill or directions, so that wide public need will be served by it.

The spring coil also serves to retain the mouthpiece connected to the transmitter, since the inner end of the mouthpiece is split and has a tendency to expand, under the manual handling which takes place when persons using the telephone play with the mouthpiece. The mouthpiece also tends to loosen when the telephone is lifted and dropped upon a table or support.

By keeping the mouthpiece tight on the front of the transmitter vibration of the mouthpiece is prevented during conversation over the line.

The hereinbefore described construction admits of considerable modifications without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

I claim as new:—

1. The combination with a telephone transmitter having a mouthpiece of conical shape provided with openings near the base thereof, of an annular ring of spring wire coiled to form a tubular structure and adapted to be snapped over the mouthpiece and to grip the base thereof, said ring having another ring of absorbent material enclosed thereby and chargeable with a vaporizable disinfectant, the vapor emitted by a ring so charged being adapted to penetrate into the mouthpiece through said base openings.
2. The combination with a telephone transmitter having a mouthpiece of conical shape provided with openings near the base thereof, of an annular ring of spring wire coiled to form a tubular structure and adapted to be snapped over the mouthpiece and to grip the base thereof, said ring having another ring of absorbent material enclosed thereby and chargeable with a vaporizable disinfectant, the vapor emitted by a ring so charged being adapted to penetrate into the mouthpiece through said base openings, and a spring coil within the first spring coil and enclosing the ring of absorbent material, the turns of the first spring coil being spaced apart and forming an open structure and the turns of the second named coil being in contact with each other, the ends of the first named coil being coupled to the ends of the second named coil.

In testimony whereof I hereby affix my signature.

CARL MILLER.
